UNITED STATES PATENT OFFICE.

OLIVER ARNOLD, OF LEICESTER, MASSACHUSETTS, ASSIGNOR OF ONE-HALF
TO MALCOM G. CLARK, OF SAME PLACE.

ROTARY MOTOR.

SPECIFICATION forming part of Letters Patent No. 531,246, dated December 18, 1894.

Application filed March 8, 1894. Serial No. 502,799. (No model.)

To all whom it may concern:

Be it known that I, OLIVER ARNOLD, a citizen of the United States, residing at Leicester, in the county of Worcester and State of Massachusetts, have invented a new and useful Rotary Motor, of which the following, together with the accompanying drawings, is a specification sufficiently full, clear, and exact to enable persons skilled in the art to which this invention appertains to make and use the same.

The object of my present invention is to provide an economical and efficient rotary motor or engine adapted for operation either by steam, compressed air, water or other fluid under pressure; said motor provided with a system of sliding gates for receiving the motive force, with gate-actuating devices automatically controlled by pressure of the operating medium for bringing said gates into their operative and non-operative positions all arranged as more fully hereinafter explained. These objects I attain by mechanism constructed and organized for operation in the peculiar manner illustrated in the drawings, wherein—

Figure 1 is a vertical section perpendicular to the axis of rotation. Fig. 2 is a vertical section longitudinal to the axis. Fig. 3 is a sectional view showing in detail one set of the operating parts. Fig. 4 is a face view of a portion of the rotator head. Fig. 5 is a transverse section at line *x x* on Fig. 3, showing the detail of the movable gate. Fig. 6 is a transverse section at line *w w* on Fig. 3, showing the detail of the actuator piston and the barrier. Fig. 7 is an exterior side view, and Fig. 8 is an exterior end view.

Referring to parts, A A' denote the body, shell or frame of the motor, consisting of a circular or ring-shaped casing A provided with a base-foot or means for its stationary support upon a suitable bed B, and side-plates A' fitted to and secured by screw bolts upon the opposite parallel sides of said circular casing A; these parts together forming or inclosing a cylindrical chamber within which the operating mechanism is arranged, the same being mounted on a central axis or shaft C that turns in bearings formed on the side plates A'. The end of the shaft extends out-

side the casing and is provided with a pulley C² or other suitable means for transmitting motion therefrom, as required. The shaft C can be provided with supporting bearings 55 separate from the plates A' when desired.

The ring casing A is provided with oppositely disposed inlet ducts or ports D and a corresponding number of exit passages E, which connect respectively with suitable supply pipes D' and discharge pipes E' which can be arranged as shown, or in any convenient manner.

Indicates the rotator-head or power-wheel having a rim formed of such dimension that 65 it will fit the interior of the shell between the side-plates A' closely, but so as to allow it free running action; said rim being connected by a web or arms with a central hub supported and fixed upon the shaft C so that the 70 rotator and shaft will turn together.

A circumferential channel G is formed about the periphery of the rotator between projecting flanges or annular side-plates f that diametrically fill the circle of the ring-casing A. The channel G serves as a space for the steam or actuating fluid by which the motor is operated, and communicates directly with the inlet ports D and exhaust passages E.

Between each of the exhaust passages E 80 and the next adjacent inlet port D there is a barrier H rigidly fixed on the ring-casing A, and extending inward so as to completely obstruct the channel passage at that position without interfering with the motion of the rotator-head.

Arranged at intervals about the rotator-head there is a series of radially movable intercepting gates I severally disposed transversely across the space G, and retractible 90 into pockets or recesses I² formed in the rim for their reception. Said gates I are respectively provided with inwardly extended stems I' that pass through suitable openings to the interior of the rim, as indicated. At a short 95 distance back from the gates and respectively corresponding therewith there are arranged presser-pistons J fitted to reciprocate within suitable openings through the rotator-rim. The inner ends of said pistons J are respectively connected with the corresponding gate-stems by means that will impart an outward 100

movement to the gate I by inward movement of the piston, and vice versa. The area of the face of the piston J is made of such proportion, relatively to the area of the gate-stem, 5 that it will receive preponderance of pressure sufficient to move the gate with the required degree of celerity.

The gate I and its actuator J are best shown in detail in Figs. 3, 4, and 5. Said parts are 10 connected, by pivoted links n or otherwise, with a rocker K having its fulcrum or axis K' carried on the rotator-wheel; said rocker serving to transmit the motion of the pressure piston to the gate-stem and gate. A suitable 15 spring L is preferably combined with the rocker to normally press outward the piston J, or retract the gate I; and a stop M, adjustable or otherwise, is provided for limiting the extent of movement of the parts. In the 20 drawings Fig. 1 the spring is shown in two forms. The spring and stop are omitted on some of the actuating sets, as either form may be used when preferred. When at outward 25 position the face of the piston J is flush, or nearly so, with the face of the rim or bottom of the channel G, (see Figs. 3 and 5) but not protruding. Hence it will pass the barrier H closely without interfering therewith.

In making the rotator F the rim is first 30 formed with the narrow flanges f', and the pockets I² then made therein by cutting transverse grooves across the rim. Then by fixing to the edges of the rim the annular plates f the ends of the slots are closed and complete 35 pockets produced for the reception of the bars or gates I; the spaces f² cut in the flanges f' serving as radial guide-ways for the ends of the gate, while the front of the gate slides against the side of the recess. The gate I is 40 best provided with a packing strip i along its outer edge where it strikes the inner surface of the casing. Small passages m formed at the back of the gates in the rear edge, and leading to the bottom of the pockets I² effects 45 equalization of pressure below and above the gate, so that the gate will move without undue resistance. The gate stem I' and the actuating pistons J can be provided with suitable packings P when desired.

50 An outlet or vent-pipe r is provided from the interior of the rotator for the purpose of overcoming the effect of any leakage thereto, and for maintaining normal atmospheric or low pressure within the central space of the rotator-head.

The ring-casing is preferably provided with 55 inwardly inclined guides e at the exit passages in front of the barriers H, which guides insure the retractive action of the gates I as 60 they approach said barriers and avoid any liability of derangement by non-action of the reciprocating parts. Plates E² attached to the casings A at the exhaust passages serve for attachment of the pipes and for the connection to the circle when the casing is 65 formed in separable parts.

The rocker devices at K, for connecting the

piston J and gate I, can be of any convenient form suitable for transmitting and transposing the inward movement of the piston to exert an outward movement of the gate, and vice versa, by pressure of the steam or operating medium.

In my improved motor, as shown, I provide two barriers H, two sets of inlet-ports D and 70 exhaust-passages E, which are severally disposed within the circular-casing; diametrically opposite each other in pairs; and with these I employ four sets of intercepting gates I and actuator-pistons J in the rotator-head, 75 it being essential to have two such gates representing each inlet-port, so that at least one of the gates will at all times be at outward position of adjustment, to intercept the passage of the steam or fluid in the channel G, 80 between each inlet D and outlet E; thus balancing the action and pressures of the motive forces at opposite sides of the axis, and producing a better, more powerful and efficiently operative mechanism. It will however be understood that if in any instance 85 desired the motor engine can be provided with a greater number of inlets, barriers and exit passages, and the rotator-head furnished with a correspondingly increased number of 90 intercepting gates and pressure-actuated pistons, the sets of mechanism being each arranged in operative order substantially as those above described.

95 By increasing the number of inlets, barriers, exits, and intercepting gates the power of the motor is increased proportionally without increase in the sectional area of the channel G or material increase in the quantity of steam required for operating a rotator 100 of given dimensions at a given speed of rotation; since the pressure acts upon a separate gate from each inlet with equal force for 105 driving the rotator, while the volume of steam used for each revolution equals only 110 the capacity of the channel G whether two, four or more sets of inlets and gate mechanisms are employed in the circle of the rotator.

115 In the operation, the steam, water, or other medium entering under pressure at D D fills 120 the space G, and its pressure acting upon the reciprocating piston J forces the same inward moving the rocker K and thereby projecting the gate I outward across the channel G and against the ring casing A; thus confining the steam between the gate I and the barrier H, and the latter being rigidly fixed to the casing the energy is exerted in moving 125 forward the gate I and thus rotating the head F in the direction indicated, according to the degree of pressure and proportional area of the gate surface; and this motion is transmitted through the center shaft C to the drive pulley. As the first gate is carried forward 130 a second gate passes the barrier H and as its actuating piston emerges from beneath the barrier to the steam inlet space it is instantly depressed and the second gate projected across the channel G to take the pressure of

the in-flowing steam. This second gate cuts off the pressure from the first described gate, which having performed its work can now be discharged. This discharge is effected by 5 passing the exit E which permits the escape of the steam from behind the gate, and as the pressure on the piston J is thus relieved the piston is forced outward by the spring and the gate retracted into its pocket I in time to 10 pass the second barrier H without interfering therewith.

In a manner similar to that here described the several gates and their actuating pistons pass the respective barriers and are consecutively brought to their outward position for holding the steam or fluid pressure and receiving the motive force until a following gate is projected; then discharged and retracted while passing the exit duct and adjacent barrier and again thrown outward in their order as the rotator head is impelled forward, thereby producing a rapid and powerful rotation of the motor shaft and drive pulley.

The operation of a gate by means of a pressure-actuated piston connected therewith being old, I do not claim such feature broadly as of my invention.

I claim and desire to secure by Letters Patent—

30 1. In a rotary motor the combination, as hereinbefore described, of the inclosed cylindrical chamber its circular casing having two opposite barriers fixed on the interior of its circle, the induction and eduction ports opening to the interior adjacent to the front and back of said barriers, and disposed diametrically opposite each other, in pairs; the circumferentially channelled rotator-head with the series of radially sliding gates and pressure-actuated gate-operating pistons therein, disposed at intervals that represent two gates relatively to each inlet, the leading gate sustaining the working pressure until, by the pressure exerted upon its actuating pistons, 45 the following gate is fully projected for controlling the channel, as set forth.

2. The rotary motor herein described, comprising the circular casing provided with a plurality of induction ports and exhaust passages, oppositely disposed in pairs within the circle, a plurality of inwardly projecting bar-

riers fixed to the casing respectively adjacent to the induction ports and obstructing the steam channel, the rotator-head having a circumferential channel and flanged rim, its periphery fitting within said circular casing, the series of transverse pockets formed in said rim and radially sliding gates therein disposed at intervals that represent two gates to each induction port, one gate retaining the working pressure while the pressure actuates the piston of the following gate said gates having stems that project through the rim, the pressure-actuated pistons respectively arranged within openings that communicate with the steam-channel in rear of said gates, the rockers connecting said pistons with the gate-stems, the retracting springs that move said pistons in opposition to the steam-pressure, and stops that limit the movement of the rockers and connected parts, all substantially as set forth.

3. In combination, as described, the inclosing casing formed of the ring portion, with close fitting side plates completely inclosing the rotator, the rotator head adapted for peripheral application of the motive force, radially sliding gates and pressure-actuated gate-operating pistons working in the rotator rim, and the relief-pass or means for exhausting the central space within said rotator-head, as set forth.

4. In a rotary motor having its rotator-head provided with a circumferentially channelled rim with radially sliding gates therein; the rim constructed as shown, with a flanged portion having the pocket-grooves for the reception of said sliding-gates cut transversely completely across the same, in combination with annular side-plates formed separate and attached to the sides of said rim, for closing the ends of said grooves, guiding the ends of said gates, and forming the outer fitting surface of said rotator-rim, substantially as set forth.

Witness my hand this 3d day of March, A.D. 95
1894.
